UNITED STATES PATENT OFFICE.

BENJAMIN F. KURTZ, OF AVALON, PENNSYLVANIA.

NUT-LOCK.

1,327,435.

Specification of Letters Patent.

Patented Jan. 6, 1920.

Application filed March 12, 1917. Serial No. 154,283.

To all whom it may concern:

Be it known that I, BENJAMIN F. KURTZ, a citizen of the United States, and resident of Avalon, in the county of Allegheny and 5 State of Pennsylvania, have invented certain new and useful Improvements in Nut-Locks, of which the following is a specification.

This invention relates to improvements in nut locks and consists in the novel details 10 of construction hereinafter described and claimed.

The object of the invention is to provide a simple, inexpensive and efficient nut locking washer constructed of a single piece of 15 flexible sheet metal and having means associated therewith adapted to engage the sides of the beam or tie with which the bolt is in engagement, and a portion of the washer having an extension thereon adapted to engage 20 the sides of a nut to lock the latter against rotation.

Other improvements and novel details in the construction and arrangement of the various parts of the apparatus will be 25 brought out more in detail in the description to follow, which, for a clear understanding of the invention, should be considered in connection with the accompanying drawing, forming a part thereof, and wherein is 30 disclosed, for the purpose of illustration, convenient and satisfactory embodiments of the invention. It is to be noted, in this connection, that minor changes in the construction and arrangement in the various parts 35 may be made without departing from the spirit of the invention or the principle of operation of the various parts.

In the drawing:

Figure 1 is a top plan view of my invention as applied;

Fig. 2 is a side elevation thereof, the beam to which the same is attached being in section;

Fig. 3 is a perspective view of my invention showing the same on its end;

Fig. 4 is a perspective view of another modification.

Corresponding and like parts are referred to in the following description and indicated

in all the views of the drawings by the same 50 reference characters.

Referring to the drawings, and more particularly to Figs. 1 and 2, wherein my invention is shown applied to a beam designated B through which is passed a bolt 10 having 55 the usual enlarged and squared head portion 11.

The nut lock of my invention comprises a washer plate having a body portion 12 provided with a longitudinally extending cut-out portion 13. Said cut-out portion provides a pair of arm members, the extremities of which are adapted to be bent downwardly as indicated at 14 and 15 into engagement with the sides of the beam or other member to be 60 clamped. The side 16 opposite the cut-out portion is bent laterally upward into engagement with the head of the bolt member which acts in conjunction with the downwardly extending arms 14 and 15 to prevent 70 rotation of the nut member.

In Fig. 4 I have shown a slightly modified form of my invention which is substantially the embodiment of the construction shown in Fig. 3 excepting the tongue portion 16' is 75 tapered thus permitting a substantial saving of material and permits an easy locking of the tongue.

Having thus fully described my invention, what I claim as new and desire to secure by 80 Letters Patent, is:

A device of the character described comprising a metal strip having a longitudinally extending cut out portion for a major portion of its length, the closed end of the 85 cut out portion being rounded to snugly embrace substantially one half of a bolt, the end opposite the rounded end portion of said strip being bent outwardly at right angles to engage with a nut when carried by 90 a bolt, and a pair of arms formed by the cut out portion and adapted to be bent at right angles to said strip in a direction opposite the other right angular bent portion for a purpose specified.

In testimony whereof I affix my signature hereto.

BENJAMIN F. KURTZ.
